US00D509846S

(12) United States Design Patent (10) Patent No.: US D509,846 S
(45) Date of Patent: * Sep. 20, 2005

(54) CARD

(76) Inventor: Anthony Collins, P.O. Box 498,
Belmont, NSW. (AU), 2280

() Term: 14 Years

(21) Appl. No.: 29/218,395

(22) Filed: Dec. 2, 2004

(30) Foreign Application Priority Data

Jun. 22, 2004 (AU) 13048/2004

(51) LOC (8) Cl. 19-01

(52) U.S. Cl. D19/7

(58) Field of Search D19/1, 2, 3, 4,
D19/5, 6, 7, 8; D20/23, 24, 29, 30; D21/438,
650; 40/124.01-124.18, 539, 672; 283/117;
446/147, 148, 149, 150
